ROUND MOLDED GYRATORY BOLTER SIEVE

Albert M. Marsh, Wauwatosa, Wis.

Application June 16, 1949, Serial No. 99,431

8 Claims. (Cl. 209—408)

1

This invention relates in general to improvements in the art of separating mixed solids into various grades, and relates more particularly to improvements in the construction and operation of sieves for vibratory bolters or the like.

The primary object of my invention is to provide an improved bolter sieve assemblage which is simple, compact and durable in construction, flexible in its adaptions, and highly efficient in use.

It has long been common practice in the flour milling industry, to employ gyratory bolters for the purpose of separating impurities from crushed grain and for separating the wholesome particles into different grades. Each of these bolters ordinarily consists of a number of similar sieves stacked upon each other, each sieve unit comprising a rectangular or square wooden frame provided with an upper layer of bolting cloth or fine screening, a layer of back wire below the screen for confining one or more freely shiftable cleaners in proximity to the lower surface of each screen, and a pan disposed beneath the back wire for conducting the material which passes through each screen and back wire away from the adjacent zone of separation. The upper extremity of each stack is provided with material supply means, while the lower end is likewise provided with flexible conduits for discharging the various grades of product, and several of the individual stacks are ordinarily mounted in the form of a symmetrical group and are simultaneously gyrated to cause the material to constantly travel downwardly over the successive superimposed screens of each stack. Because of the wooden construction of the sieve frames, the joints cannot be maintained tight and the stacks are necessarily confined within rather bulky sieve boxes, and considerable difficulty is always encountered due to shrinkage of the wood and infestation resulting from bacterial growth, while the wood is furthermore not adapted to effectively resist high temperatures such as are desirable when handling certain commodities.

It is therefore an important object of the present invention to provide an improved bolter screen and pan assemblage consisting of separable upper screen and lower pan sections adapted to be snugly superimposed or readily separated, and formed of light moulded substance so as to effectively confine the screen and back wire of each unit in normal position while permitting convenient insertion or removal of these parts and access to all other portions of the structure.

Another object of this invention is to provide a

2

circular sieve unit which besides being strong and adapted to withstand high temperatures, can be readily cast and/or machined to eliminate loose joints and to avoid corners wherein material can accumulate and cause infestation, and whereby the successive screen units may be conveniently adjusted by turning them about a central axis to provide for variable discharge of the separated particles.

10 A further object of the invention is to provide a unitary screen frame and pan assembly which may be stacked and group for gyration without necessity for providing a separate enclosure or sieve box, and wherein leakage and escape of fine material due to shrinkage and warping of the frames is substantially avoided.

Still another object of my invention is to provide an improved bolter sieve formed of a minimum number of rigid parts which may be readily constructed and assembled so as to insure an airtight and highly sanitary sieve stack adapted to be readily positioned in a group with similar stacks for vibration with the aid of common actuating mechanism.

25 An additional object of the present invention is to provide a sieve frame and pan unit in which the sieve and back wire may be detachably confined without the use of tacks or other fastening elements which are apt to become dislodged and mixed with the materials, and wherein the material passing from one separating zone to the next screen is not dropped directly upon the screen cloth but is gradually spread thereover from a side shelf thus eliminating clogging of the sieve perforations and blanketing of a large area of the screen deck with a thick layer of material.

Another object of this invention is to provide a novel gyratory bolter sieve assemblage in which the screen deck and pan may be disposed or formed so as to hasten the advancement of the material through the bolter, thus insuring maximum capacity with the use of relatively small and fewer screening units.

45 A further object of my present invention is to provide a bolter sieve unit which when stacked and properly grouped, will occupy minimum height and space, and which is also adapted for cooperation of other similar units so as to produce a maximum number of separate grades of product with the aid of a minimum number of the units.

Still another object of the invention is to provide an individual sieve frame and pan assembly

55 comprising two cooperating rigid one-piece sec-

tions formed of cast metal or plastic, and which coact to confine, the screen and back wire in a manner whereby these elements are readily renewable and the cleaners are conveniently accessible.

An additional object of this invention is to provide a round bolter sieve unit which is adapted for either right or left hand delivery of the separated materials without alteration, and wherein all outlets for the product are easily accessible, while the round construction also facilitates diversified grouping or nesting of the stacks of sieve units.

Another object of my invention is to provide an improved round moulded bolter sieve which may be manufactured in quantity at moderate cost in the form of readily cooperable and interchangeable units, and which is also self-cleaning so as to maintain sanitary conditions therein at all times.

These and other objects and advantages of the invention will be apparent from the following detailed description.

A clear conception of the features constituting the present improvement, and of the construction and operation of several typical commercial embodiments of the invention, may be had by referring to the drawings accompanying and forming a part of this specification wherein like reference characters designate the same or similar parts in the various views.

Fig. 1 is a top view of three lower sections of a stack of the improved round sieve and pan units, viewed at the line 1—1 of Fig. 2, portions of upper sections having been broken away to reveal structure of lower sections;

Fig. 2 is a central vertical section through the stack of sieve and pan units shown in Fig. 1, showing three complete units or six sections, and the section being taken along the line 2—2 of Fig. 1;

Fig. 3 is another central vertical section through the same stack assembly, taken at right angles to that of Fig. 2 and along the line 3—3 of Fig. 1;

Fig. 4 is a somewhat reduced top view of a modified upper screen section having each segmental material conducting opening divided into two adjoining parts;

Fig. 5 is a likewise reduced top view of a modified lower pan section adapted for cooperation with the upper section of Fig. 4; and

Fig. 6 is a considerably enlarged fragmentary section and partial elevation of the lowermost corner of a stack showing details of construction of the bolter sieve assembly.

While the invention has been shown and described as being especially advantageously applicable to square sieve flour bolters of the gyroscopic type, it is not my desire or intention to restrict the improved features to such construction and use; and it is also contemplated that specific descriptive terms used herein be given the broadest possible interpretation consistent with the disclosure.

Referring to Figs. 1, 2, 3 and 6 of the drawing, the typical gyroscopic bolter assemblage shown therein by way of illustration comprises in general an upright stack of superimposed composite units resting upon a special circular one-piece supporting base 8, each of the units consisting of an upper one-piece circular frame section 9 having a square or otherwise polygonal screen assembly 10 disposed centrally thereof, and a lower one-piece circular frame section 11

having a similarly polygonal pan 12 formed integral therewith and also disposed centrally thereof. These upper and lower frame sections 9, 11 are each preferably moulded and/or cast of light but durable metal or plastic, and both sections have continuous circular peripheral rims 14 provided with tapered outer bounding surfaces 15 the lower ends of which are snugly wedgingly cooperable with tapered upper bores 16 formed in the adjacent sections, when stacked upon each other.

The polygonal screen assembly 10 of each upper frame section 9 of each composite sieve unit, is provided with an externally tapered square rigid frame 17 having a sieve or screen 18 of fine wire or silk secured to its top and a back wire 19 of metal or plastic and of relatively large mesh secured to its bottom, preferably without the aid of tacks, staples, or other similar fasteners. The upper frame section 9 of each unit, has a series of inner cord-like walls 20 formed integral with its rim 14 to provide a square internally tapered recess 21 within which the screen frame 17 is upwardly insertible, and as shown in Fig. 6, the edges of the screen 18 are bent down while the edges of the back wire 19 are bent up so that all of these edges are firmly clamped between the frame 17 and the adjacent walls 20 when the screen assembly is inserted within its confining recess 21. One or more universally movable screen cleaners 22 of well known construction, are normally confined within each screen assembly 10 between the sieve 18 and the back wire 19 thereof, as depicted in Figs. 2 and 3, and these cleaners 22 travel along the back wires and coact with the lower surfaces of the sieves.

The integral cord-like walls 20 of the screen frame sections 9 are spaced from the adjacent peripheral rims 14 so as to provide segment shaped material delivery openings 24 extending downwardly through the sections 9; and one of these openings in each section 9 is either completely or partially closed and covered by a feed plate or platform 25 also formed integral with the section and disposed in approximate horizontal alignment with the adjacent sieve deck or screen 18, as shown in Figs. 1, 2 and 4. The square pans 12 which are formed integral with the lower section 11, may be inclined slightly toward their discharge openings 23 as illustrated in Figs. 3 and 6, and are each provided on their other three sides with integral walls 26 the upper edges of which are snugly cooperable with the lower edges of the adjacent screen section walls 20 so as to seal the spaces beneath the back wires 19 from the spaces directly above the fine screens 18. The pan walls 26 also cooperate with the adjacent peripheral rims 14 of the sections 11 to provide segment shaped material delivery openings 24 extending downwardly through the pan sections and adapted to be disposed in vertical alignment and communication with the similar openings in the screen sections 9; and in the modification of Figs. 4 and 5 the openings 24 are each divided into two parts by a partition 34 formed integral with the sections 9, 11.

As previously indicated, the successive screen and pan sections 9, 10 may be stacked upon each other to provide a series of superimposed composite units, and the successive sections 9, 10 of each stack may be relatively adjusted about the stack axis so as to cause any of the material discharge openings 24 of the upper sections 9

to communicate openly with any of the corresponding openings 24 of the adjacent lower section 10. When such adjustment has been effected, and the two sections 9, 10 have been brought together, the screen assemblage 10 of the upper section 9 will be locked in position within the tapered central opening 20 by the adjoining lower section 10; and the coacting sections 9, 10 of the unit may be fixed against subsequent displacement either by means of 10 dowel pins applied to registering holes 27 shown in Figs. 1, 4 and 5, or by means of ridges 28 on the bottom of each section 9, 10 and coacting with grooves 29 at the top of the next lower section as in Fig. 6. The supporting base 8 for each stack of sections 9, 10 is also provided with cord-like walls 30 cooperating with the lower ends of the walls 20 of the lowermost screen section 9, and the base section 8 is moreover provided with material discharge openings 31 and with integral suspension ears 32 radiating from its peripheral rim, as illustrated in Figs. 1, 4, 5 and 6. These ears serve to support the stacks in groups for gyration in a well known manner.

When the screen sections 9 and pan sections 11 have been constructed as above described, they are interchangeably cooperable and may be stacked upon a base 8 so as to superimpose four of the composite units upon each other. One or more of these stacks may be suspended from ordinary gyrating or vibrating mechanism with the aid of the ears 32 of the supporting bases 8 in a well known manner, and after the outlet openings 31 have been connected to the usual flexible discharge conduits and the screen or bolter stacks are being gyrated, material to be treated may be fed upon the uppermost feed platforms 25 and will thereafter advance over the uppermost screen decks or sieves 18 and in the direction of the dot-and-dash arrows indicated in Figs. 2 and 3. The rejects from the upper screen 18 will drop by gravity upon the succeeding lower feed platforms through the discharge openings 24 and over the succeeding lower screens 18 as shown in Fig. 2 and will ultimately be delivered from each stack through the lowermost right-hand discharge opening 31. The material which passes through the successive screens 18 will drop upon the adjacent pans 12 as shown in Fig. 3 and will be delivered by these inclined pans into the vertically aligned discharge openings 24 at the left being ultimately discharged by gravity through the left hand opening 31. The cleaners 22 will ride or travel along their supporting back wires 19 and will brush and vibrate the adjacent screens 18 so as to prevent possible clogging of the screen perforations during normal operation.

Because of the circular formation of the frame and base sections 8, 9, 11, these sections may be readily adjusted about the central axis of each upright stack so as to cause the screen rejects and the product passing through the screen perforations to be delivered into any of the openings 24 thus making it possible to produce numerous grades of final product with the aid of a minimum number of the composite screen and pan units. The number of grades of product may also be increased by providing partitions 34 within the openings 24 as in Figs. 4 and 5, and the feed platforms 25 avoid clogging of the screen perforations by preventing delivery of thick layers of fine material from the upper screen decks directly upon local areas of the lower

decks. The one-piece circular formation of the frame sections 9, 11 not only facilitates relative adjustment and tight sealing of the joints between the adjoining sections at the peripheral rims 14 and walls 20, 26, but also permits elimination of corners and pockets in which material might accumulate and produce infestation. The tapered formation of the screen frame receiving recesses 21 also enables convenient insertion and removal of the screens and firm retention of the sieve cloth 18 and back wire 19 without the aid of separate fastenings such as tacks, and furthermore provides for convenient access to the cleaners 22 and internal surfaces.

From the foregoing detailed description, it will be apparent that my present invention provides an improved gyratory bolter sieve assemblage, which by virtue of its round and molded construction is in fact exceedingly simple and compact in construction, and highly efficient in operation while also being flexible in its adaptations. The tight joints afforded by the coacting tapered surfaces 15 and bores 16 of the superimposed sections, make it unnecessary to provide special sieve boxes such as used with prior bolters, and the one-piece molded construction of the sections 9, 11 and base 8 not only provide a much stronger frame structure but also produce a far more sanitary and readily cleanable assembly 30 in which all parts are conveniently accessible for thorough cleansing. By forming these frames of metal, they may also be utilized to withstand high temperatures, and the round frame structures can also be accurately machined and finished to produce tight joints between the adjacent stacked sections. The round rims 14 cooperate with the square screens 10 to permit adjustment by quarter-turns, and either the dowel pins openings 27 or the ridges 28 may be 40 utilized to hold the sections in the desired positions of adjustment.

The construction of Figs. 1, 2 and 3 may be utilized to produce five separations, while the modified structure of Figs. 4 and 5 may be employed to produce nine independent products. The round construction also facilitates close nesting of a group of two, three, four or more stacks of the sections, and also provides material delivery passages 24 of large cross-section thus enhancing the capacity and avoiding accumulation of product therein. The improved screen and pan units may also be produced in quantity at relatively low cost, and may be manufactured in various sizes for diverse uses.

It should be understood that it is not desired to limit this invention to the exact details of construction or to the precise mode of use of the bolter units herein shown and described, for various modifications within the scope of the appended claims may occur to persons skilled in the art.

I claim:

1. In a sieve assemblage, a unitary upper frame section having a circular peripheral rim and a series of integral walls forming a square central opening within the rim, a unitary lower frame section also having a circular peripheral rim snugly interlockably cooperable with said upper section rim and being provided with an integral square pan bounded on three sides by walls snugly cooperable with said upper section walls, and a separable screen confined within said upper section opening by said lower section.

2. In a sieve assemblage, a unitary upper frame section having a circular peripheral rim and a

series of integral walls forming a square central opening within the rim bound by upwardly and inwardly tapered surfaces, a unitary lower frame section also having a circular peripheral rim snugly interlockably cooperable with said upper section rim and an integral square pan bounded on three sides by walls snugly cooperable with said upper section walls, and a separable screen bounded by tapered surfaces confined within said upper section opening surfaces by said lower section, said screen having an upper sieve deck and a lower back wire disposed in horizontal alinement respectively with the upper and lower edges of said upper section walls.

3. In a sieve assemblage, a unitary upper frame section having a circular peripheral rim and a series of integral walls forming a square central opening within the rim bounded by upwardly and inwardly tapered surfaces, a unitary lower frame section also having a circular peripheral rim snugly interlockably cooperable with said upper section rim and an integral square pan bounded on three sides by walls snugly cooperable with said upper section walls, and a separable screen bounded by upwardly and inwardly tapered surfaces confined within said upper section opening by said lower section, said upper section walls and rim cooperating to provide a series of segment shaped material discharge openings surrounding said screen and one of said discharge openings being covered by a feed platform disposed in horizontal alinement with the top of said screen.

4. In a sieve assemblage, a unitary upper frame section having a circular peripheral rim and a series of integral walls forming a square central opening within the rim, a unitary lower frame section also having a circular peripheral rim snugly interlockably cooperable with said upper section rim and an integral square pan bounded on three sides by walls snugly cooperable with said upper section walls, and a separable screen insertible only from beneath said upper section and confined within said upper section opening by said lower section, said upper and lower sections being relatively adjustable about their central vertical axis to vary the relative positions of said screen and pan.

5. In a sieve assemblage, a unitary upper frame section having a circular peripheral outer rim and a series of integral inner walls forming a square central opening within the rim, a unitary lower frame section also having a circular peripheral outer rim and an integral square central pan bounded on three sides by walls vertically alineable with said upper section walls, and a separable screen confined within said upper section opening above said pan by said lower section walls.

6. In a sieve assemblage, a unitary upper frame section having a circular peripheral outer rim and a series of integral inner walls forming a square central opening within the rim, a unitary

5 lower frame section also having a circular peripheral outer rim and an integral square central pan bounded on three sides by walls vertically alineable with said upper section walls, and a separable screen confined within said upper section opening above said pan by said lower section walls, said upper section rim being bounded by a downwardly and inwardly tapered outer surface snugly cooperable with a similarly tapered bore formed in said lower section rim to centralize said frames.

7. In a sieve assemblage, a unitary upper frame section having a circular peripheral outer rim and a series of integral inner walls forming a square central opening within the rim, a unitary lower frame section also having a circular peripheral outer rim and an integral square central pan bounded on three sides by walls vertically alineable with said upper section walls, and a separable screen confined within said upper section opening above said pan by said lower section walls, said upper section opening being bounded by an upwardly and inwardly tapered surface and said screen being bounded by a similarly tapered surface wedgingly cooperable with said opening bounding surface.

8. In a sieve assemblage, a unitary upper frame section having a circular peripheral outer rim and a series of integral inner walls forming a square central opening within the rim, a unitary lower frame section also having a circular peripheral outer rim and an integral square central pan bounded on three sides by walls vertically alineable with said upper section walls, and a separable screen confined within said upper section opening above said pan by said lower section walls, said upper section rim being bounded by a tapered outer surface wedgingly cooperable with a tapered bore formed in said lower section rim and said upper section opening being bounded by another tapered surface wedgingly cooperable with a tapered bounding surface formed on said screen.
